No. 761,661.

PATENTED JUNE 7, 1904.

J. CONRAD.

NON-REFILLABLE BOTTLE.

APPLICATION FILED MAR. 13, 1904

NO MODEL.

UNITED STATES PATENT OFFICE.

JOHN CONRAD, OF BALTIMORE, MARYLAND.

NON-REFILLABLE BOTTLE.

SPECIFICATION forming part of Letters Patent No. 761,661, dated June 7, 1904.

Application filed March 12, 1904. Serial No. 197,790. (No model.)

To all whom it may concern:

Be it known that I, JOHN CONRAD, a citizen of the United States, residing in the city of Baltimore and State of Maryland, have invented new and useful Improvements in Non-Refillable Bottles, of which the following is a specification.

My invention relates to an improved non-refillable bottle, and has for its object to provide a cheap, simple, and highly-efficient device that is adapted to be molded into the neck of a bottle for the purpose of preventing the refilling of a bottle after its original contents have been dispensed.

With this briefly-stated object in view my invention comprises a bottle having a valve-seat adjacent the lower end of its neck against which operates a disk valve which is normally held adjacent to the valve-seat by a plug that is inserted and held into the lower end of the bottle-neck, said plug having a recess in its lower end into which the valve opens and a zigzag passage through which the contents of the bottle escape when the valve is open, and in order to avoid any possibility of the valve obstructing the escape of the liquid I propose to enlarge the lower end of the bottle upon one side, said enlargement forming practically a continuation of the zigzag passage.

My invention also comprises certain details of construction and novelties of combination and arrangement, as will be fully described in the following specification and pointed out in the claims, reference being had to the drawings, in which—

Figure 1 is a perspective view of a bottle embodying my improvement. Fig. 2 is a vertical sectional view drawn through the neck of a bottle with my improvement in place.

Fig. 3 is a similar view showing the bottle tilted, the location of the valve, and the escape of the liquid. Fig. 4 is a horizontal sectional view drawn on about the line 4-4 of Fig. 2. Fig. 5 is a vertical section of the plug, said section being taken in the line 5-5 of Fig. 2. Fig. 6 is a detail perspective view of the plug, and Fig. 7 is a detail perspective view of the valve.

In the practical application of my invention

I may employ any suitable form or shape of bottle A, having an elongated neck A', and upon one side of the neck near its base I provide an enlargement A², which is recessed or concaved upon its inner side, the purpose of which will appear hereinafter. A valve-seat A³ is arranged within the bottle at the base of the neck and surrounds an opening A⁴. The upper face of the seat is ground to provide a perfectly flat seat.

Within the lower end of the neck of the bottle I arrange a plug B, having a zigzag passage-way B' extending throughout nearly its entire length and a recess B² in its extreme lower end. This recess is circular in shape, and its upper wall is preferably arranged upon an incline, as shown at B³. One side of the plug is cut out, as shown at B⁴, and this cut-out portion is arranged opposite the enlarged portion A² of the neck of the bottle, so that a continuous passage-way is provided between the upper and lower ends of the plug, and it will be noticed, particularly by reference to Fig. 2 of the drawings, that one of the partitions B⁵ that forms the zigzag passage-way of the plug has its outer edge terminating on a line with the concavity of the enlargement of the neck. The zigzag passage-way also extends entirely through the plug at diametrically opposite points for the purpose of permitting the neck of the bottle to be pressed slightly into the plug, as shown at C, which will prevent the withdrawal of the plug after it has been arranged in position, and it may be said here that of course these inwardly-extending portions C may be made while the bottle is still hot, or they may be provided for in the molding of the bottle. A disk valve D is arranged within the recess B² of the plug and has its lower face ground to provide a smooth bearing-surface which is adapted to set smoothly and tightly upon the valve-seat. Two or more perforations D' are provided in the valve near its periphery for the purpose of permitting air and liquid to find their way between the valve and its seat when the bottle is tilted, which decreases the tendency of the valve to stick. These apertures also permit a certain amount of air to enter the bottle when it is tilted, as it will be

understood that the bottle is not always tilted to the position shown in Fig. 3 of the drawings; but when tilted in the opposite direction the valve attains a position opposite to that shown in the drawings, nor will the perforations always be in the position shown, as the valve will undoubtedly revolve; but no matter in what position the valve may be or the bottle tilted the perforations will permit a certain amount of air to enter the bottle. In molding the plug in a bottle the valve is placed within the recess of the plug and held against the upper wall by means of a wire or tape E, which is of course previously arranged throughout the zigzag passage and its lower end bent over the edge of the valve, as shown at E', which firmly holds the valve in place. The opposite end of the wire or tape is connected to a ring E", by which the wire or tape may be withdrawn after the bottle has been thoroughly cooled, and of course it will be understood that this wire or tape is made of sufficiently flexible material to permit this operation and that it is not withdrawn until after the bottle has been filled, when the valve will readily drop to its seat.

It will thus be seen that I provide an exceedingly simple, cheap, and highly-efficient device that contains but few parts, and therefore rendering it impossible of getting out of order.

Having thus fully described my invention, what I claim, and desire to secure by Letters Patent, is—

35 1. A device of the kind described, the combination of a bottle having an enlarged portion formed upon one side of its neck providing a concavity within the neck, a valve-seat arranged at the lower end of the neck, said 40 valve-seat having an opening arranged therein, a plug arranged in the lower end of the bottle-neck, said plug having a zigzag passage-way arranged therein nearly throughout its entire length and a recess arranged in its lower 45 end, the said plug also having a portion of its

periphery cut out, said cut-out portion being arranged opposite the concavity of the neck of the bottle, and a valve arranged within the recess of the plug adapted for engagement with the valve-seat, said valve being perforated near its periphery, all for the purpose specified.

2. In a device of the kind described, the combination of a bottle having a valve-seat arranged at the base of its neck and an opening 55 arranged therein, a plug arranged within the neck and having a zigzag passage-way therein, said passage-way extending to the periphery of the plug at diametrically opposite points, depressions formed in the neck and extending 60 into the said passage-way, the said plug also having a recess in its lower end which communicates with the said zigzag opening, and a valve arranged within the recess and adapted to rest upon the valve-seat, as specified. 65

3. In a device of the kind described, the combination of a bottle having an enlarged portion formed upon one side of its neck providing a concavity inside the neck, a valve-seat arranged in the lower end of the neck and having an opening produced therein, a plug arranged within the neck, said plug having a zigzag passage-way produced therein and a recess formed in its lower end, the upper wall of the recess being the partition between the 75 zigzag passage-way and the recess, the said wall being arranged upon an incline, one side of the plug having a cut-out portion alining with the said concavity of the neck, one of the partitions forming the zigzag passage-way in 80 the plug terminating on a line with the concavity of the neck and a disk valve operating within the recess of the plug and adapted for engagement with the valve-seat, all substantially as and for the purpose specified.

JOHN CONRAD.
